CORD APPLIQUÉ FOR HANDBAGS AND
OTHER ARTICLESWilliam Cavalluzzo, Whitestone, Long
Island, N. Y.

Application January 14, 1941, Serial No. 374,340

2 Claims. (Cl. 2—278)

This invention relates to new and useful improvements in a cord appliquéd for handbags and other articles.

The invention proposes the construction of appliquéd material as mentioned which is characterized by a relatively stiff base sheet of cloth material, a top work sheet of cloth material on the base sheet, and a novel arrangement of appliquéd upon these sheets.

More specifically, the invention proposes to provide a base solid cord appliquéd design on the sheets, and to superimpose on this appliquéd design an open work top appliquéd design.

In another form of the invention it is contemplated to superimpose on the base solid appliquéd design more than one layer of appliquéd designs to enhance the construction and appearance of the finished article.

Still further the invention proposes to so arrange the appliquéd construction that it may be applied in accordance with conventional methods of applying appliquéd. The designs may be suitably prepared by the use of the usual buckram or prepared chemical paper guides which may be burned out or dissolved out of the finished article upon completion of the appliquéd patterns.

Still further the invention proposes to so construct the appliquéd design that it may be formed from cords of various types and on base materials of various kinds.

Still further the invention also proposes a novel construction by which certain areas or layers of the appliquéd construction may be stiffened or rendered completely flexible when desired.

Another object of the invention is the construction of a design as mentioned which is simple and durable and which may be manufactured and sold at a reasonable cost.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:

Fig. 1 is a fragmentary plan view of cord appliquéd material constructed in accordance with this invention.

Fig. 2 is a fragmentary enlarged sectional view taken on the line 2—2 of Fig. 1.

Fig. 3 is a plan view of another piece of cord appliquéd material constructed according to another form of this invention.

Fig. 4 is a fragmentary enlarged sectional view taken on the line 4—4 of Fig. 3.

Fig. 5 is a fragmentary plan view of another piece of cord appliquéd material constructed in accordance with still another form of this invention.

Fig. 6 is a fragmentary enlarged sectional view taken on the line 6—6 of Fig. 5.

The cord appliquéd material for handbags and other articles, in accordance with this invention, includes a relatively stiff base sheet of cloth material 10 upon which there is superimposed a top work sheet of cloth material 11. A solid cord appliquéd design 12 is appliquéd on these sheets. An open work top appliquéd design 13 is appliquéd on the solid design 12.

The base sheet 10 may comprise muslin, buckram or other material suitable as a base material. The top work sheet 11 may comprise soft muslin, satin, silks or other desirable top materials. The solid cord appliquéd design is constructed from cord material which is sewn upon the sheets 10 and 11 in close formation in any selected design. The design shown in Fig. 1 is of square configuration. The open work top appliquéd design 13 is shown upon the appliquéd design 12 and the sheets 10 and 11.

In Figs. 3 and 4 a modified form of the invention has been disclosed in which the cord appliquéd for handbags includes a relatively stiff base sheet of cloth material 14 upon which there is a top work sheet of cloth material 15. A base solid cord appliquéd design 16 is appliquéd on the sheets 14 and 15. At certain areas of this design 16 there are other and smaller intermediate appliquéd designs 17 of solid cord arrangement. Superimposed on these intermediate areas 17 there are open work top appliquéd designs 18. With this arrangement there are three layers of appliquéd cords at certain areas of the article. The base appliquéd design 16 is shown as of spiral formation, the intermediate appliquéd design 17 of square formation. The top appliquéd designs 18 are of other ornamental arrangements.

In Figs. 5 and 6 another modified form of the invention is disclosed which distinguishes from the prior form in the construction and arrangement of the intermediate appliquéd design 17.

In accordance with this form of the invention these intermediate designs 17' are appliquéd on an intermediate piece of cloth material 20. This intermediate sheet 20 has strips of cloth material 21 secured to its bottom face by lines of stitches 22 forming a passage 23 which extends

from one edge to an opposed edge of the appliquéd design 17'.

Stiffening strips 24 are removably mounted in these passages 23. Each stiffening strip 24 has an aperture 25 at one end by which it may be gripped so that it may be pulled out from the passage 23. At the other end each strip 24 has several laterally extending prong portions 25 cut from the material thereof and resiliently engaging the lines of stitches 22 to releasably hold the strip 24 in position in the passage 23.

In Fig. 5 two of the reinforcement strips 24 are shown arranged beneath the intermediate appliquéd design, for stiffening this area. When desired these strips 24 may be removed as previously explained.

The stiffening strips 24 act to stiffen certain areas of the appliquéd design while other portions remain soft and pliable to the touch of one's hand. This combination of soft pliable areas and stiffened areas appeal to the touch sense and adds interest to the article having such appliqués.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I

claim as new, and desire to secure by United States Letters Patent is:

1. Appliquéd for handbags and other articles, comprising a base sheet of cloth material, a base solid cord appliquéd design on said sheet, small areas of solid cord intermediate appliquéd designs on said base appliquéd design, and a top appliquéd design on said intermediate appliquéd designs, said intermediate appliquéd designs having base sheets, and means for reinforcing the latter base sheets, comprising strips on the latter base sheets secured with lines of spaced parallel stitches forming passages extending to opposite sides, and stiffening strips removably mounted within said passage.

2. Appliquéd for handbags and other articles, comprising a base sheet of cloth material, a base solid cord appliquéd design on said sheet, small areas of solid cord intermediate appliquéd designs on said base appliquéd design and a top appliquéd design on said intermediate appliquéd designs, said intermediate appliquéd designs having base sheets, and means for reinforcing the latter base sheets, comprising strips on the latter base sheets secured with lines of spaced parallel stitches forming passages extending to opposite sides, and stiffening strips mounted within said passage, each stiffening strip having projecting lateral elements engaging the said lines of stitches.

WILLIAM CAVALLUZZO.
